UNITED STATES PATENT OFFICE.

HENRY H. BAILEY, OF SEATTLE, WASHINGTON, ASSIGNOR TO H. E. GLEASON COMPANY,
OF KING COUNTY, WASHINGTON.

LIGHT-BULB PROTECTOR.

1,290,482.

Specification of Letters Patent.

Patented Jan. 7, 1919.

Application filed October 3, 1918. Serial No. 256,708.

To all whom it may concern:

Be it known that I, HENRY H. BAILEY, citizen of the United States, residing at Seattle, in the county of King and State of Washington, have invented certain new and useful Improvements in Light-Bulb Protectors, of which the following is a specification.

This invention relates to improvements in light bulb protectors and has for its principal object to provide a protector of this nature which will permit of an ordinary light bulb being handled fairly roughly without danger of breaking the bulb. Such lights are largely used in shops and are not only in danger of flying pieces of metal or other material but in the large overhead lights such as used in shipyards and the like the bulbs are liable to breakage due to the rapid changing of these lights from place to place.

My invention will be more fully described in the following specification, shown in the accompanying drawings and finally pointed out in the appended claims.

In the drawings Figure 1 is a side elevation of my improved light bulb protector showing a bulb supported in position therein. Fig. 2 is a fragmentary side elevation of the same showing a form of clamp.

Referring now more particularly to the drawings numeral 1 indicates wires which form a kind of basket, the lower ends of each of these wires are hooked upon a ring 2 and the upper ends are secured to a cross member 3 which is circular in plan. 4 indicates a strap member bent into the form as shown and which is secured to the cross member 3 by screws 5. 6 indicates the usual light wire and 7 the socket. 8 indicates the usual light bulb. Riveted at 9 to the strap 4 may be a supplemental strap 10 through which passes the lower end of a clamp 11 which has a binding screw 12. 13 indicates coil springs one of the ends of each of which is fastened to the light socket 7 and each of their other ends are fastened at 14 to the strap 4. 15 represents similar springs whose lower ends are fastened at 16 to a ring 17 which fits around the bulb, the opposite ends of the springs 15 are fastened at 18 to the

cross member 3. There may be any suitable number of springs 13 and 15 but I have found that four of each is sufficient.

From the above it will be seen that I have provided an efficient protection for an ordinary light bulb so that the bulb may be handled roughly without danger of breakage, due to the protection of the basket formed by the wires 1 and the strap 4. The bulb 8, in a sense, floats within the basket and is cushioned in every direction. The bulb works freely within the ring 17 and yields in all directions.

While I have shown a particular form of embodiment of my invention, I am aware that many minor changes therein will readily suggest themselves to others skilled in the art without departing from the spirit and scope of my invention, and I, therefore, desire to avoid being limited to the exact form shown and described.

Having described my invention, what I claim as new and desire to protect by Letters Patent, is:

1. In an article of the class described the combination of a rigid hollow member adapted to contain an ordinary electric light bulb, means engaging the top and bottom portions of a lamp for holding the latter within the said member in a full floating relation thereto.

2. In an article of the class described the combination of a plurality of wires formed into a container including a bottom ring and means for fastening the lower ends of the wires thereto, a cross piece and means for fastening the upper ends of the wires thereto, a strap member attached to the said cross piece and means for yieldingly clamping the said cross piece to a beam or the like, a plurality of upper coil springs which positions the light socket in a floating relation within the said container; a plurality of lower coil springs and means for connecting the same to the light bulb proper so as to render the bulb in full floating relation to the said container, the last mentioned means including a ring which receives the bulb in yielding relation thereto.

3. A lamp holder of the class described comprising a housing, upper springs hav-

ing their lower ends connected to the housing, means connecting the upper ends of said springs and forming an abutment for the upper end of a lamp, lower springs connected at their upper end to the interior of the housing, and an open support connecting the lower ends of the lower springs and adapted to receive the lower portion of a

bulb of a lamp, where the lamp will be suspended by said springs.

10

In testimony whereof I affix my signature in the presence of a witness.

HENRY H. BAILEY.

Witness:

MARGUERITE LEYDA.
